CONTACT STRUCTURE FOR THREE-POSITION RELAY MECHANISMS

Oscar S. Field, Rochester, N. Y., assignor to General Railway Signal Company, Rochester, N. Y.

Application August 20, 1937, Serial No. 160,077

7 Claims. (Cl. 200—6)

This invention relates, in general, to a contact structure for electrical devices, and has more particular reference to a contact arrangement for use on a "searchlight" type light signal for use on railroads.

In practice it has been found that a larger number than usual of contact fingers is desirable in many situations and with this requirement in mind it is proposed, in accordance with the present invention, to provide a contact arrangement which is compact and economical, both of material and space, and still is very durable and dependable in operation.

With the above and other objects in view, it is proposed to provide a contact arrangement, for a three-position light signal, which provides eight sets of front-and-back contact fingers.

Further objects, purposes and characteristic features of the present invention will appear as the description progresses, reference being made to the accompanying drawing showing, in a wholly diagrammatic manner, and in no manner whatsoever in a limiting sense, one form which the invention can assume.

In the drawing:

Fig. 1 is a front elevational view of one form of the invention, as applied to a "searchlight" type signal.

Fig. 2 is a side elevational view of the invention as shown in Fig. 1.

Fig. 3 is a sectional view on the line 3—3 of Fig. 2, viewed in the direction of the arrows.

Fig. 4 is a plan view of one of the fixed contact carrying members.

Fig. 5 is a plan view of one of the movable contact carrying members.

Fig. 6 is a sectional view on line 6—6 of Fig. 1, viewed in the direction of the arrows.

The invention has been illustrated as applied to a "searchlight" type light signal as employed on railroads and of the general type such as shown in the patent to O. S. Field, No. 1,835,150, granted December 8, 1931.

The manner in which the motor element of the light signal operates the contacts is of the same general form as shown in the O. S. Field application, Ser. No. 7,565, filed February 21, 1935.

Only so much of the light signal and the motor and operating means thereof will be described in the following description, as is deemed useful for the purpose of disclosing the present invention, any further details in this respect being obtainable from the above referred to disclosures.

Referring now to the drawing, and first to Fig. 1, there is here shown a portion of a light signal

to which the present invention is applied. A portion of the motor element is shown at 1, and this motor element rocks a shaft on a knife-edge bearing 2, to rock a sector 3 carrying operating arms 4 and 5, one at each end of the sector, for rocking centering weights 6 and 7 about their pivots, such as the pivot 8 of the weight 6, whereby to actuate contacts.

In describing this invention, only one-half of the contact arrangement has been shown in the drawing, since it is a symmetrical arrangement, and the side to the left of the center line 9 of Fig. 1 is identical with the parts shown to the right of this center line. Accordingly, a description of the portions shown at the right clearly should suffice for the disclosure of the complete arrangement.

Below the centering weights 6 and 7 is a contact holding member, made of insulating material, and preferably molded, as of Bakelite, or the like, and comprising a thin, flat, plate-like member 10 of a general oval form, having rigidly attached thereto at each of its ends, a forwardly projecting head member 11, only the head member at the right end of plate 10 being shown in the drawing.

Referring now to Fig. 2, it can be seen how the counterweights and the plate and head members are carried. A frame member comprising two portions 12 and 13, are bolted together as by bolts 14, to carry the centering weights, as 6, on the pivot 8, there being adjustable front and back stops 15 and 16 for the centering weight 6 and like stops 17 and 18 for the centering weight 7.

Connected to the frame member 13 by means of screws 19, is the plate 10, together with its integral, forwardly projecting heads 11, the screw 19 passing through a boss 20 on each head and on its inner end receiving a nut 21, thereby securely fastening each contact carrying member, as 10, to the frame of the signal and positioning them beneath the centering weights 6 and 7.

Each centering weight, as the centering weight 6, has fastened to it a contact operating arm 22 which is molded into, or otherwise rigidly attached to a movable contact carrying head 23. This head 23 carries two spaced plate like members 24, of insulating material, molded into the head 23 or otherwise rigidly fastened thereto. Each of the contact carrying plate members 24 carries two movable contacts 25, of low resistance conducting material, formed in the shape of a V, and fastened to its carrier by projecting through the carrier and being riveted over on the rear

side, as at 26, to thereby fasten itself and a soldering ear 27, to the carrier.

Thus each centering weight, when moved from its shown position against its back stop, to a position against its front stop, upon the motor element being energized in the proper direction, operates to move a head 23, and with it the four spaced, separate, movable contact members 25.

Carried by each of the heads 11, one on each side thereof, is a fixed contact carrying member 28, of insulating material, and of a triangular form, as shown in Fig. 4, at the upper end of which are carried two spaced fixed contact members each comprising a receiving cup 29, carrying a contact block 30 of silver impregnated carbon or the like. Each cup 29 is riveted, or otherwise suitably fastened, to its carrier 28, and has connected to it a soldering ear 31.

As best seen in Figs. 2 and 3, each fixed contact carrying member 28 is pivoted at its lower point, through an opening 32 therein, on a pin, having a shouldered portion 33 and a reduced portion 34, and held, as shown in Fig. 3, between the head member 11 and a side plate 35 of insulating material, having a grooved out portion 36 for accommodating the lower end of the carrier 28. Each of the side plates, there being one on each side of each head 11, is bolted to its head by two bolts and nuts 37, each of these bolts 37 serving as a connection post for one of the movable contact members 25, a wire, as 38, connecting a soldering ear 27 with the inner end of a bolt 37, with an external lead in wire, such as 39, connected to the outer end of the bolt 37. Thus it can be seen that each of the four movable contact members, on each of the heads 11, is connected to one of the four bolts or terminal posts 37 fastening the two side plates 35 to the head 11.

Each of the fixed contact carrying plates 28 is perforated, as at 40, to receive a pin 41 passing through the two plates on the head 11, and projecting beyond the outer sides of each plate, and carrying locking nuts 42 at one end, and a head 43 at the other end. Between the head 43 and a follower 44 a biasing spring 45 is loosely received on the pin 41. The pin 41 is loosely received in the openings 40 in the carriers 28 and in holes 46 in the head 11.

With the arrangement as above described, it can be readily seen that the single pin 41, together with its single biasing spring 45, operates to bias both of the carriers 28 inwardly toward each other and toward the movable contacts 25.

Carried on the plate 10, as best seen in Fig. 1, are two connection posts 47 and 48, for one of the heads 11, and 59 and 60 for the other head, and two other connection posts 49 and 50, each one serving for both of the heads 11. The two inner fixed contact members 29 for each head 11, as shown in Fig. 1, are connected respectively by flexible leads 51 and 52, and 57 and 58, to the terminal posts 47 and 48, and posts 59 and 60. The two outer fixed contact members 29 are connected through their soldering ears 31, and flexible leads 53 and 54 passing through tubes 55 and 56, and 61 and 62, to the terminal posts 49 and 50.

As described above, the four movable contact members 25 are electrically connected, each to one of the posts 37, with the outer end of each of these posts 37 carrying a lead in wire 39, there of course being four of these lead in wires as shown best in Fig. 6. As shown in Fig. 1, there are four lead in wires 63, 64, 65 and 66 connected to the terminal posts 59, 47, 60 and 48 respectively.

It can thus be seen that there are six independent circuits controlled by the contact arrangement as described above, two of which circuits each includes two front and two back contacts, which circuits pass through the terminal posts 49 and 50. The other four circuits each include one front and one back contact and each of these circuits includes one of the terminal posts 47, 49, 59 and 60 and one of the terminal posts 37.

While the particular arrangement of circuits and the devices which they control, are not an essential part of the present invention, and the contact arrangement above described is not limited to any particular arrangement, it is contemplated in one form of this invention to have the two circuits passing through the terminal posts 49 and 50 control two separate red indications, with two yellow indications and two green indications controlled respectively by the circuits passing through the terminal posts 47-48, and 59-60. Thus, when the motor element is de-energized, the contacts are made up as shown in Fig. 1, to complete the two circuits for the red indications; when the motor element is energized to lift counterweight 6, the two yellow indication circuits will be closed, while when the motor element is energized to lift counterweight 7, the two green indication circuits will be closed.

It will be obvious that other combinations of connections may be used whereby different combinations of contact operations may be provided, such for instance as dependent front and back contacts and the like as are well known in the signalling art.

Thus, to briefly summarize the structure as disclosed above, it will be seen that the structure involved comprises two counterweights, one or the other of which can be raised from its biased position, at any one time, to thereby move four separate and independent movable contact members to cause two movable contacts to make contact with two fixed contacts and to make two other movable contacts to break connection with two other fixed contacts, the centering weight 6 operating the four movable contacts carried by the head 23, while the other centering weight operates a corresponding set of movable contacts when the motor element is energized in the opposite direction.

Thus there has been provided a contact arrangement having eight separate pairs of contacts, each comprising a front and a back contact member.

Furthermore, an arrangement has been provided whereby two fixed contacts cooperate with two movable contacts, with the fixed contacts supported by a single pivot pin, as 33, whereby to permit a rocking movement as well as a pivoting movement of the carrier 23 to permit the contact pressure to equalize in amount and prevent any possibility of one of the two pair of contacts making up while the other might still be spaced.

Furthermore, in combination with this pivoted fixed contact carrier member 28 is a single spring and a single pin, respectively 45 and 41, which operate to bias two carriers 28 inwardly, thus making a very simple and compact and economical structure for the number of contacts involved.

The above rather specific description of one form which this invention can assume, is given by way of example only and is not intended in any manner whatsoever, in a limiting sense. It is to be understood that it is intended this application should cover all such modifications, al-

ternatives, substitutions, and variations as may appear useful or desirable, and as come within the spirit and the scope of the present invention.

Having described my invention by disclosing one specific embodiment thereof, I now claim:

1. In a contact organization for use in light signals and the like, in combination, a rectangular support, two contact fingers pivoted one at each of two opposite sides of the support, a single elastic means biasing both fingers inwardly toward each other and against the sides of the support, a fixed contact on each finger, a movable contact carrier, a movable contact on the carrier and positioned to cooperate with the two fixed contacts, and means for operating the contact carrier relatively to the fixed contacts. 5
2. In a contact organization, in combination, a supporting block of generally rectangular outline, a pivot pin on each of two opposite sides of the block, a fixed contact carrying plate of insulating material at each side of the block and each having one of its ends pivoted on one of said pins, means biasing the carrying plates inwardly toward each other and against the sides 10 of the block, two separate, spaced fixed contacts at the free end of each carrying plate, four movable contacts for cooperating with the four fixed contacts respectively, and means for operating the movable contacts. 15
3. In a contact organization, in combination, a supporting block of generally rectangular outline, a pivot pin on each of two opposite sides of the block, a fixed contact carrying plate of insulating material at each side of the block and each having one of its ends pivoted on one of 20 said pins, means biasing the carrying plates inwardly toward each other and against the sides of the block, two separate, spaced fixed contacts at the free end of each carrying plate, a movable contact carrying head, two head plates of insulating material carried by the head, and two spaced movable contacts on each head plate for cooperating, respectively, with the two fixed contacts on each said carrying plate, and means for moving the carrying head relatively to said block. 25
4. In a contact organization, in combination, a supporting block of generally rectangular outline, a pivot pin on each of two opposite sides of the block, a fixed contact carrying plate, of insulating material, at each side of the block, and each having one of its ends pivoted on one of said pins, two separate, spaced fixed contacts at the free end of each carrying plate, four movable contacts for cooperating with the four fixed contacts respectively, means for operating the movable contacts, and means for biasing the carrying plates inwardly toward each other and against the sides of the block, including, a rod 30 passing loosely through the block and both of the plates and projecting, at each end, beyond the plates, a head at each end of the rod, and compressible means about the rod and between one of the heads and one of the plates. 35
5. In a contact organization, in combination, a supporting block of generally rectangular outline, a pivot pin on each of two opposite sides of the block, a fixed contact carrying plate of insulating material at each side of the block, and each having one of its ends pivoted on one of said pins, two separate, spaced fixed contacts at the free end of each carrying plate, a movable contact carrying head, two head plates of insulating material carried by the head, two spaced movable contacts on each head plate for cooperating, respectively, with the two fixed contacts on each said carrying plate, means for moving the carrying head relatively to said block, and means for biasing the carrying plates inwardly toward each other and against the sides of the block, including, a rod passing loosely through the block and both of the plates and projecting at each end beyond the plates, a head at each end of the rod, and compressible means about the rod and between one of the heads and one of the plates. 40
6. In a contact organization, in combination, a support block, a fixed contact carrying plate of insulating material, two spaced fixed contacts connected to the plate at one end thereof, the other end of the plate being tapered, a grooved side plate, two bolts connecting the side plate to the block with the groove facing toward the block, a pivot pin having a shouldered portion spanning the opening formed by the groove and the side of the block and a reduced portion received in the side plate, the tapered end of the carrying plate being loosely received on the shouldered portion of the pivot pin to form a universal joint, a movable head of insulating material, two spaced movable contact members carried by the head and so spaced as to cooperate with the two spaced fixed contacts, and means to operate the said head. 45
7. In a contact organization, in combination, a support block, a fixed contact carrying plate of insulating material, two spaced fixed contacts connected to the plate at one end thereof with the other end of the plate tapered, a grooved side plate, two bolts connecting the side plate to the block with the groove facing toward the block, a pivot pin having a shouldered portion spanning the opening formed by the groove and the side of the block and a reduced portion received in the side plate, the tapered end of the carrying plate being loosely received on the shouldered portion of the pivot pin to form a universal joint, a movable head of insulating material, two spaced movable contact members carried by the head and so spaced as to cooperate with the two spaced fixed contacts, flexible conducting means connecting the movable contacts to the two bolts, respectively, and means to operate the said head. 50
